The ornamental design for a trunk, as shown and described.

DESCRIPTION

FIG. 1 is a front perspective view of an embodiment of a trunk;

FIG. 2 is a front view of the embodiment of the trunk of FIG. 1;

FIG. 3 is a rear view of the embodiment of the trunk of FIG. 1;

FIG. 4 is a top view of the embodiment of the trunk of FIG. 1;

FIG. 5 is a bottom view of the embodiment of the trunk of FIG. 1;

FIG. 6 is a right side of the embodiment of the trunk of FIG. 1;

FIG. 7 is a left side view of the embodiment of the trunk of FIG. 1;

FIG. 8 is a front perspective view of an embodiment of a trunk;

FIG. 9 is a front view of the embodiment of the trunk of FIG. 8;

FIG. 10 is a rear view of the embodiment of the trunk of FIG. 8;

FIG. 11 is a top view of the embodiment of the trunk of FIG. 8;

FIG. 12 is a bottom view of the embodiment of the trunk of FIG. 8;

FIG. 13 is a right side of the embodiment of the trunk of FIG. 8; and,

FIG. 14 is a left side view of the embodiment of the trunk of FIG. 8.

The broken lines show environmental items and portions of the trunk and form no part of the claimed design. The drawings include grey surface shading that represents contour and not surface ornamentation or color. The trunk is shown with break lines indicating a symbolic break in length. The appearance of any portion of the trunk between the break lines forms no part of the claimed design.
